UNITED STATES PATENT OFFICE

HERBERT E. PLISHKER, OF FLUSHING, NEW YORK, ASSIGNOR TO WESTINGHOUSE LAMP COMPANY, A CORPORATION OF PENNSYLVANIA

DESIGN FOR A WRAPPER FOR A BOX OR CARTON

Application filed March 1, 1930. Serial No. 34,710. Term of patent 3½ years.

To all whom it may concern:

Be it known that I, HERBERT E. PLISHKER, a citizen of the United States, residing in Flushing, in the county of Queens and State of New York, have invented a new, original, and ornamental Design for a Wrapper for a Box or Carton, of which the following is a specification, reference being had to the accompanying drawing, forming part thereof.

The figure is a plan view of a wrapper showing the complete design.

I claim:

The ornamental design for a wrapper for a box or carton as shown.

HERBERT E. PLISHKER.
